PLAY SLACKS

Lloyd I. Belden, St. Paul Park, Minn.

Application November 25, 1953, Serial No. 27,792

Term of patent 14 years

(Cl. D3—17)

To all whom it may concern:

Be it known that I, Lloyd I. Belden, a citizen of the United States, residing at St. Paul Park, in the county of Washington and State of Minnesota, have invented a new, original, and ornamental Design for Play Slacks, of which the following is a specification, reference being had to the accompanying drawing, forming a part hereof.

In the drawing:

Fig. 1 is a front elevational view of play slacks, showing my new design;

Fig. 2 is a side perspective view of the same;

Fig. 3 is a rear elevational view of the same, and

Fig. 4 is a horizontal sectional view taken on the line 4—4 of Fig. 3.

I claim:

The ornamental design for play slacks, as shown.
